DESIGN FOR A BUTTER SLICER
OR THE LIKE

Henry B. Cohen, New York, N. Y., assignor to
Acme Aluminum Mfg. Co., New York, N. Y.,
a firm composed of Henry B. Cohen and Henry
Weiss

Application April 10, 1946, Serial No. 128,426

Term of patent 3½ years

(Cl. D44—29)

To all whom it may concern:

Be it known that I, Henry B. Cohen, a citizen of the United States and a resident of the city, county, and State of New York, have invented a new, original, and ornamental Design for a Butter Slicer or the like, of which the following is a specification, reference being had to the accompanying drawing, forming part thereof, in which:

Fig. 1 is a perspective view of a butter slicer embodying my design.

Fig. 2 is a bottom plan view, and

Fig. 3 is a vertical section taken on the line 3—3 of Fig. 2 of a butter slicer embodying my design.

Fig. 4 is an enlarged perspective view of a detail of Fig. 1 to which the arrows 4—4 point.

I claim:
The ornamental design for a butter slicer or the like, as shown.

HENRY B. COHEN.
